REINFORCING FORM FOR WALL STRUCTURES

Filed May 10, 1920

2. sheets-sheet 2

UNITED STATES PATENT OFFICE.

JOSEPH W. BRAGSTAD, OF OAK PARK, ILLINOIS.

REENFORCING FORM FOR WALL STRUCTURES.

Application filed May 10, 1920. Serial No. 380,062.

To all whom it may concern:

Be it known that I, JOSEPH W. BRAGSTAD, residing at Oak Park, in the county of Cook and State of Illinois, have invented certain 5 new and useful Improvements in Reenforcing Forms for Wall Structures, of which the following is a specification, reference being had to the accompanying drawings, and the letters of reference marked thereon, which 10 form a part of this specification.

My invention relates to an expandible metal form which is used in wall structures to reinforce and contain the interior wall and receive the plastering.

15 It is therefore an object of my invention to construct a metal device which can be shipped in unassembled or unexpanded form and readily assembled or expanded when needed.

20 It is a further object of my invention to construct a form to which the plastering will readily adhere and be supported thereon.

It is also an object of my invention to construct the same economically and involving the least amount of labor, and in such a way that one may readily be placed upon another and interlocked therewith.

Other objects and advantages reside in the 30 novel structure or means whereby I attain these objects, as will be apparent from the disclosures in the specifications and drawings.

In the drawings—

35 Fig. 1 is a top plan view of a metal form involving my invention.

Fig. 2 is a section thereof on the line 2—2 of Fig. 1, showing the unexpanded form.

40 Fig. 3 is a section similar to Fig. 2 but showing the section in expanded form.

Fig. 4 is a section showing an interlocking connection used in my device.

Fig. 5 is a section showing how two forms are interlocked when one is placed upon the 45 other.

Fig. 6 is a section on line 6—6 of Fig. 5.

Fig. 7 is a perspective view near the end of a form showing a reenforcing post and the manner of securing the same.

50 Fig. 8 is a section on the line 8—8 of Fig. 7.

Fig. 9 is a section through a wall embodying my invention showing the reenforcing posts in perspective.

55 Fig. 10 is a section showing an applica-

tion of my invention in building construction.

Fig. 11 shows an application of my invention to a retaining wall.

As shown on the drawings:

In practising my invention, I preferably cut and stamp a plurality of sheet metal plates with interfitting parts, whereby a pair of plates 1 may be interlocked to constitute a collapsed form as shown in Figs. 1 and 2, 65 and whereby a second form may be interlocked therewith after said forms have been expanded, and are ready for use. It is contemplated that any number of forms may be thus interlocked in building a wall. 70

One way of accomplishing my purpose is illustrated in the present embodiment of my invention in which each plate 1 has a plurality of tongues 2. The outer ends of these tongues have lugs 7 which are preferably formed by stamping the metal, each plate has also a plurality of apertures 3, the number thereof corresponding to the number of tongues on the other plate. These apertures are preferably formed by cutting slits 80 in the metal and bending the metal outwardly on opposite sides thereof to form flaring parts 4 and 5, the flaring parts 4 having lugs 6, which are preferably formed in cutting the metal and bent at right angles, 85 to the flaring parts. These parts 4 and 5 are yieldable and allow the tongue members to swing from inclined to vertical position, so these yieldable walled apertures may be termed hinge connections. It will be noted, 90 that in the collapsed form of the device, these apertures are obliquely arranged and the tongues 2 are inclined or obliquely arranged. In assembling these plates to constitute the collapsed forms, the tongues 2 of 95 each plate are inserted in the apertures 3 of the other plate, the lugs 7 on the tongues interlocking with the lugs 6 on the flaring parts 4. In the assembled collapsed form, one plate is somewhat in advance of the 100 other as shown in Fig. 2.

It is contemplated that these collapsed forms should be shipped to the place where they are to be used. But before using them, they are expanded as shown in Fig. 3, 105 whereby the tongues yield or bend at their bases and assume positions which are substantially at right angles to the plates and the interlocking parts yield and assume the positions shown in Fig. 4, in which the 110

flaring parts 4 and 5 have been bent outwardly to a greater extent than they were in the collapsed form. The interlocking apertures with their flaring parts 4 and 5 are thus yielding and may be termed a hinge connection for the tongues 2 which are also yieldable and which can be swung or bent from collapsed to expanded position while interlocked in said apertures. Thus the 10 plates might be said to be interlocked in variable spaced relation. The ends 8 of the tongues 2 are narrower in width than the main parts of the tongues which are located between the plates; consequently, a pair of 15 shoulders are formed on each tongue, one shoulder on each edge thereof, in a plane through approximately the point 9 in Fig. 4. The proportion of parts are such that the shouldered parts of the tongues are slightly 20 wider than the apertures 3, precluding the tongues thereby from slipping through the apertures. Each of the tongues 2 has preferably a corrugation 10 for the purpose of giving it strength and rigidity.

25 In constructing a wall with these forms it is desirable that a form which is placed upon another form be interlocked therewith. For this purpose I have constructed each plate with a pair of slits 11 and bent to a slight degree outwardly the metal adjacent thereto to form lips 12 as shown in Figs. 1 and 5. These slits 11 are located near the upper edge of the plates 1; the opposite edge of each plate having tongues 13 formed by 30 cutting away the metal adjacent thereto, each tongue 13 having a lug or spur 14 stamped therefrom. And when one form is placed upon another form, the tongues 13 of the upper form are directed into the slits 11 35 of the lower form, the tongues 13 will pass through the slits 11 until the lugs 14 pass behind the lips 12 at which point the two forms become interlocked.

40 As the outer surface of each plate will receive the plastering, it is necessary that the plates be constructed that the plaster will adhere thereto and it is also desirable to have a guide to indicate the thickness of the rough plaster. I preferably cut and stamp 45 longitudinal shelves or guides 15 from each plate, the shelves or guides being bent outwardly at substantially right angles to the plates. They also support the plaster, and the slots 17 which are caused by the stamping out of these shelves, may be filled with 50 concrete and afford rough surfaces to permit the plaster to adhere thereto. If desirable lugs 16 may also be struck from the plates to assist in holding the plaster. These 55 shelves 15 and lugs 16 extend outwardly approximately the entire thickness of the rough plaster wall, and thus they form the guide as to the thickness of the plaster wall.

60 It is contemplated that these forms when 65 expanded may be used in the construction of

any walls or floors, and in Figs. 9, 10 and 11 I have illustrated a few uses thereof. These forms are made so that when expanded the width thereof will correspond to the width of the desired wall. The interior of these forms are filled with concrete or a similar cementing substance to form the wall proper. Longitudinal reinforcing rods 19 may be used as shown in said figures, the forms being added one on top of the other and interlocked therewith as the occasion requires. Fig. 9 shows a construction of such a wall in which vertical reinforcing rods 18 are secured by means of wires 19^a to the outer sides of the plates near the ends thereof 70 and beyond the shelves or guides 15. These wires may bind the posts to both plates, as shown in Figure 3. These rods 18 are designed to be embedded in the rough plaster on the plates, and the rough plaster receives 75 the proper finished facing.

In Fig. 10 I have shown a ceiling 20 and a floor 21 thereabove which is supported by a wall embodying my invention, and in the right hand end of said figure I have shown 80 a ceiling 22, which may be supported between a pair of walls embodying my invention.

In Fig. 11 I have shown how my invention 85 may be employed in making a broad retaining wall. As shown, a pair of walls such as shown in Figure 9 are constructed a distance apart with spacing and reinforcing rods 23 spanning the entire width thereof, after which the space between the walls may 90 be filled with concrete or the like, and a well aligned and finished wall may be thus produced. While three vertical rows of rods 19 are shown in Fig. 11, only the outer row 95 thereof is necessary.

100 It will accordingly be seen that I have devised a metal frame which may be assembled and shipped in a collapsed form and which may be readily expanded when it is desired to use the same, which may be interlocked 105 with another, and which has plastering faces and guides for indicating the thickness of the rough plaster.

I am aware that numerous details of construction may be varied through a wide 110 range without departing from the principles of this invention, and I therefore do not propose limiting the patent granted otherwise than necessitated by the prior art.

115 I claim as my invention—

1. An expandible form for a wall comprising a pair of spaced plates, each plate having obliquely extending tongues and flaring walled apertures, the ends of said tongues being provided with integral lugs 125 stamped therefrom, and the lugs of the tongues of one plate being interlocked with the flaring walls of the apertures of the other plate.

2. An expandible form for a wall com- 130

prising a pair of spaced plates, one of said plates having obliquely extending tongues provided with lugs stamped therefrom and the other plate being provided with apertures having flaring parts with which the ends of said tongues are interlocked, said form being adapted to be expanded to bring said tongues into perpendicular relation with said plates.

10 3. An expandible form for a wall comprising a pair of spaced overlapping members, one of said members having obliquely extending tongues and the other member having apertures with flaring parts in which the ends of said tongues are interlocked, said form being adapted to be expanded whereby said tongues are brought into substantial perpendicular relation with said plates.

15 4. An expandible form for a wall comprising a pair of spaced overlapping plates, one of said plates having yieldably inclined extending members and the other plate having means interlocked with said members 20 to produce a collapsed form adapted to be expanded.

5. A form for a wall comprising a pair of spaced overlapping plates, one of said plates having apertures and the other of said plates 30 having oblique yieldable tongues interlocked in said apertures and yieldable from an oblique position to a perpendicular position for expanding said form.

6. An expandible form for a wall comprising a pair of spaced plates, one of said plates having yieldable tongues and the other plate having yieldable parts interlocked with said tongues whereby said plates may be collapsed or expanded.

7. In a form for a wall, a plate member having flaring walled apertures adapted for receiving parts of another plate in parallel relation therewith, and marginal tongues having spurs struck therefrom for the purpose described.

8. In a form for a wall, a plate member having flaring walled apertures, obliquely extending tongues, and marginal slits for the purpose described.

9. In a form for a wall, a pair of spaced plates, one of said plates having tongues provided with interlocking parts and the other of said members being provided with flaring walled apertures, interlocked with said parts, both of said plates having marginal interlocking parts for engaging and securing another form in alinement therewith.

In testimony whereof I have hereunto subscribed my name in the presence of two 60 subscribing witnesses.

JOSEPH W. BRAGSTAD.
